UNITED STATES PATENT OFFICE

164,161

BASEBALL CLOWN DOLL

George Irving Fischer, San Francisco, Calif.

Application September 26, 1950, Serial No. 12,360

Term of patent 7 years

(Cl. D34—4)

To all whom it may concern:

Be it known that I, George Irving Fischer, a citizen of the United States of America, resident of the city and county of San Francisco and State of California, have invented a new, original, and ornamental Design for a Baseball Clown Doll, of which the following is a specification, reference being had to the accompanying drawings, forming a part hereof:

Fig. 1 is a front elevational view of a baseball clown doll showing my new design;

Fig. 2 is a side elevational view of the baseball clown doll shown in Fig. 1, and

Fig. 3 is a black elevation thereof.

I claim:

The ornamental design for a baseball clown doll, substantially as shown.

GEORGE IRVING FISCHER.
